UNITED STATES PATENT OFFICE.

JAMES LALLY, OF TEKAMAH, NEBRASKA.

HALTER.

SPECIFICATION forming part of Letters Patent No. 416,227, dated December 3, 1889.
Application filed May 20, 1889. Serial No. 311,445. (No model.)

To all whom it may concern:

Be it known that I, JAMES LALLY, a citizen of the United States of America, residing at Tekamah, in the county of Burt and State of Nebraska, have invented an Improved Halter, of which the following is a specification.

My invention consists in the construction and combination of metal coupling devices and leather straps and buckles, as hereinafter set forth, to produce a neat, strong, and durable halter that can be readily adjusted and fitted to horses of different sizes.

Figure 1 of the accompanying drawings shows a square frame adapted for connecting three leather straps. Fig. 2 shows an oblong frame adapted for fixing one strap thereto and sliding on another strap. Fig. 3 is a perspective view of a coupling device adapted for adjustably connecting the nose-band and a hitching-strap. Fig. 4 is a view of a coupling device adapted for connecting the nose-band and throat-latch and keeping them a proper distance apart. Fig. 5 is a perspective view of a complete halter.

The frame *a* (shown in Fig. 2) has a T-shaped integral and arched frame *b* on its top.

The ring *c* (shown in Fig. 3) is double half-way round, and thereby adapted for connecting the ends of the overlapping parts of the nose-band and a hitching-strap.

The coupling device (shown in Fig. 4) consists of a straight portion *d*, that has an integral rectangular frame *f* at one end, and an integral rectangular frame *g* at the other end that is provided with an integral cross-bar *h*.

No. 1 is a leather strap fixed to a common ring or frame and adjustably connected with the frame *a* to extend vertically over the face of a horse.

No. 2 is a leather strap fastened at one end

to the double ring *c* and passed under the part *b* on the frame *a*, and adjustably connected with double portion of the ring *c* in such a manner that it can be fitted around a horse's nose.

No. 3 represents a throat-latch formed of two straps that are fixed to the ring at the top end of the strap No. 1. The long one is passed through the frame *g* on the end of the bar *d* and detachably and adjustably connected with the free end of the short strap by means of a buckle, so it can be fitted around a horse's neck. The nose band or strap No. 2 is extended through the frame *f* in such a manner that when a hitching-strap 55 is fixed to the ring *c* and stretched it will pull the nose-band partially through the frame *f*, and in so doing draw it close around the horse's nose, as required to apply force to his nose and to hold him securely.

I claim as my invention—

An improved halter comprising a strap No. 1, having a ring fixed to its top end and adjustably connected at its lower end with a metal coupling device composed of a frame *a*, 65 that has an integral arched T-shaped bar *b*, a strap No. 2, extended through and between the said frame *a* and the bar *b* and connected with a double ring *c*, a strap No. 3, adapted to encircle a horse's neck, fixed to the ring at 70 the top end of strap No. 1, and a metal connecting-bar *d*, having an integral frame *f* at one end and an integral frame *g* at the other end provided with a cross-bar *h*, arranged and combined substantially as shown and described.

JAMES LALLY.
